UNITED STATES PATENT OFFICE.

SILAS BYRD, OF CHILTON, TEXAS.

GLOBE DRAFT-SHIELD.

1,194,953.

Specification of Letters Patent. Patented Aug. 15, 1916.

Application filed November 30, 1915. Serial No. 64,344.

To all whom it may concern:

Be it known that I, SILAS BYRD, a citizen of the United States, residing at Chilton, in the county of Falls and State of Texas, have 5 invented new and useful Improvements in Globe Draft-Shields, of which the following is a specification.

This invention relates to globe draft shields and the principal object of the invention is to provide a simple and efficient device which may be firmly attached to an ordinary lamp chimney or globe and which will prevent draft or sudden gusts of wind from blowing out the lamp.

10 Further objects of the invention will appear as the following description is read in connection with the accompanying drawing, which forms a part of this application, and in which:—

15 Figure 1 is a perspective view of the device. Fig. 2 is a vertical sectional view showing the device mounted upon a lamp globe.

20 Referring more particularly to the drawing, 1 represents a substantially circular body which tapers from the base to the upper end thereof so as to produce an attenuated exit 2. At the base of the body there is secured an annular flange 3 having parallel sides and overlapped freely engaged ends 4. These ends are separated as shown at 5 from the body and passing across the same is a spiral spring 6 permanently connected to a lug 7 at one end and adjustably 25 connected to a lug 8 at the opposite end by means of a bolt 9 upon which is mounted a thumb nut 10. The top of the body is covered by a cap 11 having depending flanges 12 to cover the side exits 13 formed in the body. The cap is also provided with openings 14 in its body portion and the body 1 is provided with apertures 15 placed immediately above the flange 3 and of somewhat 30 smaller diameter than the apertures 13.

40 When the device is placed upon a globe as shown in Fig. 2 it is limited in its down-

ward movement by fingers 16 which engage over the upper edge of the globe as shown. These fingers may be either struck up from the body of the device or riveted to the same 50 as shown.

What is claimed is:—

1. A device of the class described comprising a hollow frusto-conical body, an annular split flange carried thereby, adjustable 55 means connecting the ends of said flange for drawing the latter together thereby constricting said flange, and means for preventing top draft into the globe.

2. A device of the class described comprising a hollow frusto-conical body, an annular split flange carried thereby, a yieldable connection between the opposite ends of said flange, means for adjusting the tension of said connection, and means for preventing 60 top draft into the globe.

3. A device of the class described comprising a hollow frusto-conical body, an annular split flange carried thereby, means for supporting said body upon the globe, and 70 limiting the downward movement of the body thereon, a yieldable connection between the opposite ends of said flange, means for adjusting the tension of said connection, and means for preventing the top draft into 75 the globe.

4. A device of the class described comprising a hollow frusto-conical body, an annular split flange carried thereby, a lug carried by the opposite ends of said flange, a 80 spring having one end terminally secured to one of said lugs, a bolt secured to the opposite terminal of said spring and adjustably associated with the other of said lugs whereby to constrict said flange, and means for 85 preventing top draft into the globe.

In testimony whereof I affix my signature in presence of two witnesses.

SILAS BYRD.

Witnesses:

JOE YEATS,
EDGAR CALVERY.
